UNITED STATES PATENT OFFICE.

PERLEY R. GLASS, OF BROOKLINE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

GROMET-SETTING MACHINE.

1,373,500.

Specification of Letters Patent. Patented Apr. 5, 1921.

Application filed June 16, 1916. Serial No. 103,924.

To all whom it may concern:

Be it known that I, PERLEY R. GLASS, a citizen of the United States, residing at Brookline, in the county of Norfolk and State of Massachusetts, have invented certain Improvements in Gromet-Setting Machines, of which the following description, in connection with the accompanying drawings, is a specification, like reference characters on the drawings indicating like parts in the several figures.

This invention relates to machines for setting gromets and washers in sheet material. Its object is to provide a machine of novel and improved organization possessing advantages in point of construction and operation over those heretofore known.

A great many machines for setting eyelets and gromets in a regular series and relatively close to each other, as in shoes and corsets, are provided with mechanism for punching the holes and for feeding the work step by step. On the other hand, when the eyelets or gromets are to be very widely separated from each other, it is not feasible to provide automatic feeding mechanism and consequently in doing work of this kind it has heretofore been the practice to punch the holes by a separate machine when the work may be conveniently transferred from the punching machine to the fastener-inserting machine, but when the work is relatively large and clumsy and would entail considerable difficulty in transferring it from the punching machine to the fastener-inserting machine, as in the case of sails, awnings and floor coverings, it has been a practice to punch the holes with a hand punch in the vicinity of the fastener-inserting mechanism. This practice has facilitated the work to a considerable extent but has not resulted in the maximum degree of efficiency obtainable.

With the above problem in view I have found that the work may be greatly facilitated and that a great deal of time may be saved by incorporating into the fastener-inserting machine as an integral part thereof an automatic punching mechanism capable of being operated independently of the fastener-inserting mechanism. Accordingly a feature of the present invention consists in a single machine comprising automatic punching mechanism and automatic fas-

tener-inserting mechanism capable of being operated independently of each other and arranged in such relation to each other that no undue effort is required and no appreciable loss of time is required to shift the work from the punching instrumentalities to the fastener-inserting instrumentalities. Preferably, and as shown, the machine is provided with a shaft from which each of the said mechanisms receives its operating motion through the agency of disconnectible clutch mechanism, the two clutch mechanisms being controllable independently of each other so that the punching mechanism may be operated while the fastener-inserting mechanism remains at rest and vice versa.

Another feature of the invention consists in novel mechanism for automatically operating the raceway of a fastener setting machine. It is desirable to move the raceway from delivering position early in the operative movement of the setting die and to move the raceway toward delivering position late in the reverse movement of the die. It is also desirable to maintain the raceway positively under control in all of its movements. These results are attained as herein shown by providing coöperating cam slot and roller, one on the raceway and the other on a reciprocatory member, the cam slot being shaped to impart the required movements to the raceway and being provided with means for confining the roller against movement away from the operative edge of the cam slot.

It will be apparent that many features of the invention are in no sense limited in their application to a machine for setting gromets and washers but may be embodied to good advantage in machines for setting eyelets or other fasteners.

These and other features of the invention will be best understood and appreciated from the following description of a preferred embodiment thereof selected for purposes of illustration and shown in the accompanying drawings, in which,—

Figure 1 is a view of the machine in front elevation;

Fig. 2 is a view of the machine in side elevation;

Fig. 3 is a similar view of the clutch mechanism for the punch;

Fig. 4 is a view of the machine in sectional elevation showing the setting mechanism;

Fig. 5 is a view in elevation of the clutch for the setting mechanism;

Figs. 6 and 7 are views of the raceway operating mechanism and associated parts.

The machine is provided with a main driving shaft and with a reciprocating 10 punch and set arranged side by side and provided with separate clutch mechanisms by which either the punch or the set may be independently operated. As herein shown the machine is organized to operate upon 15 work presented at an angle of substantially 45° this having been found a convenient arrangement in dealing with large pieces of heavy work which must be dragged into position before the machine and held in 20 place while the machine is operating.

The main shaft 8 is journaled in the upper portion of the machine frame 2 and is provided with a driving pulley 10. A loose sleeve 20 having an eccentric portion formed 25 on its left end is mounted upon the shaft 8 adjacent to the hub of the pulley 10. The loose ring 22 of a Horton clutch is journaled upon the sleeve 20 and is so related to the driving pulley that the sleeve 20 may be 30 engaged with it for the purpose of operating the punch. The ring 22 has a tooth 24 shaped to be engaged by a spring plunger 26 carried in an arm 28 pivotally mounted upon a stud at the rear of the shaft 8. The 35 arm 28 extends forwardly and is provided with a hole through which extends the upper end of a treadle rod 30. The rod 30 is notched at its rear side and arranged to engage one edge of the hole through the 40 arm 28. A spring pressed pin 32 in the outer end of the arm normally holds the rod 30 in its engaged position so that when the rod 30 is depressed the arm 28 will be 45 disengaged to disengage the tooth 24 and permit the clutch to engage. A pin 36 is set in the periphery of the sleeve 20 so as to strike the upper end of the rod 30 when the sleeve 20 is rotated, swinging it forwardly and disengaging it from the edge of the hole in the 50 arm 28. After being disengaged the arm 28 is immediately returned to operative position by a spring plunger 38 acting on the lower side of the arm.

The eccentric part of the sleeve 20 operates an eccentric strap 40 which at its forward end is connected to the knuckle joint of a pair of toggle links 41 and 42. The link 41 is pivoted on a transverse shaft 44 mounted in the upper part of the machine frame. The lower link 42 is connected to a collar 46 fast upon the plunger 48 which carries at its lower end a solid tubular punch 50. The punch 50 is rigidly but adjustably retained in the plunger 46 being backed up 60 by a filling piece 49 which in turn is adjust-

ably supported within the plunger by an adjusting pin 51.

The punching die is formed in a cylindrical block 52 received in a socket in the work table 54. A graduated scale 55 extends 70 along the rear side of the work table. By placing any given point on the work opposite one of the graduations on the scale the desired distance between the edge of the work and a hole or between successive holes 75 may be determined.

The punching mechanism above described is operated by depressing the treadle rod 30 whereupon the toggle 41—42 is straightened and the punch 50 is depressed perforating 80 the work in combination with the punching die 52. After the punching operation the plunger is lifted to the position shown in Fig. 2 and the machine brought to rest by the action of the stop arm 28 regardless of 85 whether or not the starting treadle is held down.

The shaft 8 carries a cam 12 in which runs a roller 14 on a cam lever 16, the lever 16 being fulcrumed upon a shaft 18 in the 90 machine frame. The cam lever 16 is connected at its upper end through a link 58 to toggle links 60 and 62 similarly arranged to the toggle above described. It will be noted that the upper links of both toggles are 95 made double as shown in Fig. 1 and engage the upper end of the lower link between them. The lower link 62 is connected to a collar 66 secured to a plunger 68 carrying at its lower end the topset 70. A tube 72 is arranged within the plunger 68 above the upsetting die 70 and bears at its upper end against the lower end of an adjusting pin 76 threaded into the plunger. By turning the screw 76 the set may be adjusted downwardly in the plunger either to increase the setting pressure or to be located properly in the required setting position. A center spindle of the usual construction is yieldingly mounted in concentric relation with the upsetting die being backed up by a compression spring disposed within the plunger 68. 100

The bottom set 86 is mounted in the upper end of a plunger 87 having a cam roller 88 115 at its lower end which is arranged to run upon the surface of a cam 89 pivoted upon a stud 90 to the frame. The plunger 87 has also a downwardly extending arm carrying a pin 92 disposed within a cam track 93 120 parallel to the surface of the cam 89. The cam 89 is connected through a link 94 to the lower end of a long lever 96 pivoted upon the shaft 18 above mentioned. At its upper end the lever 96 carries a roller 97 arranged to run in cam groove 98. The cam groove 98 is so shaped as to bring the bottom set 86 to rest in its uppermost position with a washer in place upon it. After the setting operation has taken place the bottom 125 130

set is lowered to receive a new washer. An adjusting pin 99 threaded into the bottom of the plunger 87 provides convenient means for adjusting the position of the bottom set 5 to control the pressure exerted in the setting operation or to locate the set with respect to the work table 54.

The washer raceway 100 and washer hopper 104 are mounted upon a link 103 10 which extends between the upper ends of a pair of pivoted links 101 and 102. The link 103 has a pair of dowel pins arranged to coöperate with sockets in the raceway 100 and a hand nut 105 by which the raceway 15 may be clamped in place upon the link. An oscillatory movement is imparted to the washer raceway through a link 106 which is connected to the lower end of a two-part lever having at its upper end a cam roller 20 arranged to run on a peripheral cam 112. The cam lever is made in two parts to facilitate adjustment of the raceway relatively to the lower setting tool. As shown the part 110 carries the cam-roll 111, and the 25 part 108 is pivotally connected to link 106. Both parts are loosely mounted on stud 18, the lower end of part 110 being forked and being provided with adjusting screws 113 that abut against opposite edges of part 108 30 so as to transmit motion from one part to the other. A spring 115 is arranged to counteract the cam 112. The cam 112 is shaped to permit the raceway 100 to advance when the bottom set 86 is depressed and to retract 35 the raceway after the bottom set has been elevated sufficiently to engage the endmost washer in the raceway.

Gromets are supplied to the set 70 by a raceway 6 which is pivotally mounted to 40 swing about a pair of cone screws 83 set in ears formed on the machine frame. A gromet hopper of usual construction is mounted upon the upper end of the raceway but has been omitted from the drawings. 45 At its lower end the raceway 6 is curved to extend beneath the set 70, being arranged to swing from the position shown in the drawings outwardly to an inoperative position out of the path of the set. To this end 50 a plate 84 having a cam slot 85 is secured to the raceway and a coöperating roller 81 is mounted upon an arm 80 which extends outwardly from the plunger 68. The cam slot 85 is so shaped that during the initial portion 55 of the downward movement of the plunger 68 no motion is imparted to the raceway. As soon, however, as the topset has entered the endmost gromet the roller 81 encounters an inclined portion in the 60 edge of the cam slot 85 which causes the raceway 6 to be swung outwardly to its inoperative position. During the remainder of the downward movement of the set the shape of the slot 85 is such as to impart no 65 further movement to the raceway. In the

upward movement of the plunger 68 the roller 81 moves idly to a point near the upper end of the slot 85 before it imparts any movement to the raceway, acting to shift the raceway into delivering position 70 just before the machine comes to rest.

It will be noted that the width of the slot 85 varies on account of the dissimilar character of its opposite edges and that throughout a portion of its length it is of 75 greater width than the cam roller 81. In order to maintain the roller 81 positively in engagement with the proper edge of the slot a plate 150 having a cam slot 151 formed therein is movably mounted upon 80 the rear side of the plate 84. The plate 150 is provided with a pair of inclined slots 152 into which project a pair of pins set in the plate 84, the pins and slots coöperating to limit the movement of the plate 150 to a 85 path substantially parallel to one of the inclined edges of the slot 85. The roller 81 projects both through the slot 85 and the slot 151 and the latter slot is so shaped as to act upon one surface of the roller 181 90 while the latter traverses the wide portion of the slot 85. The operation of this portion of the raceway operating mechanism will be apparent from an inspection of Figs. 6 and 7 from which it will be seen that, in 95 traversing the wide portion at the upper end of the slot 85 in the downward movement of the plunger, the roller 81 is acted upon at its right side by the edge of the slot 151 in the plate 150 and, near the conclusion 100 of the downward movement, the roller 81 encounters a portion of the bottom of the slot 151 and shifts the plate 150 downwardly and toward the right into the position shown in Fig. 7. In the upward movement of the plunger the roller 81 passes into the wide portion of the slot 85 near the upper limit of its movement and is here 105 acted upon at its left side by the opposite edge of the slot 151. In completing its upward movement, the roller 81 encounters the upper end of the slot 151 and shifts the plate 150 upwardly and toward the left into its initial position.

When it is desired to effect the setting 115 operation the shaft 8 is set in motion by clutch mechanism which will now be described. The ring 120 of a Horton clutch is located upon the right side of the driving pulley 10 and is provided with a tooth 121 arranged to be engaged by a spring pin 122 mounted in an arm 123 pivotally mounted on the shaft 124. A spring 125 tends normally to hold the pin 122 in position to disengage the clutch. A treadle arm 126 is 120 pivotally mounted on the shaft 124 and is provided with a spring piece 128. The spring piece is provided with a notch which fits normally over the pin 130 projecting from the arm 123. When the treadle rod is 125 130

depressed the arm 123 is swung outwardly through the medium of this pin. Continued depression of the treadle brings the tail of the piece 128 into engagement with 5 an adjustable stop 132 set in a portion of the frame. This disengages the piece 128 from the pin 130, thus permitting the arm 123 to return the clutch pin 122 to its operative position regardless of whether or not 10 the treadle is released or held depressed.

A sleeve 140 provided with teeth 141 surrounds the shaft 8 and coöperates with the latch piece 142 pivoted on the pin 130 in the arm 123. This catch prevents rebound 15 of the ring 120 when the tooth 121 encounters the stop pin 122. A spring 144 normally presses the latch 142 toward the collar 140.

The operation of the machine will be clear 20 from the foregoing description but it may be briefly outlined as follows: The work is presented to the machine with the point at which the first gromet and washer are to be set in line with the punch 50. The treadle 25 rod 30 is then depressed and the punch operates to perforate the work, being brought to rest in its uppermost position. The work is then moved toward the left to carry the punched hole into position upon the bottom 30 set 86 to which a washer has already been supplied by the raceway 100. The treadle rod connected to the arm 126 is then depressed and the shaft 8 and the cams carried thereby are set in rotation. The topset 35 70 descends taking a gromet from the raceway 6 which it forces through the hole in the work and the washer and against the upsetting surface of the set 86 thereby clenching the end of the gromet barrel upon the 40 outer surface of the washer. The plunger 68 is then elevated and the machine comes to rest with all parts in their initial position.

Having thus described my invention, I 45 claim as new and desire to secure by Letters Patent:

1. A fastener-setting machine comprising a frame having a work table and guideways perpendicular thereto and arranged in a 50 series parallel to a possible path of feeding movement of the work along the table, a punching tool and a setting tool arranged to slide in said guideways respectively, two disconnectible clutch mechanisms arranged 55 in bearings in said frame, means controlled by one of said clutch mechanisms to operate the punching tool, and means controlled by the other clutch mechanism to operate the setting tool.

60 2. A machine for setting fasteners, having in combination, a frame having a main shaft journaled therein, a pair of plungers arranged for movement in parallel paths, one carrying a setting tool and the other a 65 punching tool, a pair of toggle links for op-

erating each of said plungers, one link of each pair having a common fulcrum shaft, and connecting mechanism between the shaft and the respective toggles.

3. A machine for setting fasteners, having 70 in combination, a reciprocatory plunger, a movable raceway, and operating mechanism including a roller on one member and a slot in the other, said slot being wider than the roller for a portion of its length, 75 and a plate shaped to confine the roller while passing the wide portion of said slot.

4. A machine for setting fasteners, having 80 in combination, a reciprocatory plunger, a movable raceway, and operating mechanism including a roller on one member and a slot in the other, said slot having a wide portion with an inclined edge, and a slotted plate movable in a direction parallel to said inclined edge.

5. A machine for setting fasteners, having 85 in combination, a reciprocatory plunger, a movable raceway, and operating mechanism including a roller on one member and, in the other, a slot having a wide portion with 90 an edge inclined to the path of the plunger, and a slotted plate having an oppositely arranged wide portion and inclined edge movably mounted adjacent to the slot first mentioned.

6. A machine for setting fasteners, having 95 in combination, a reciprocatory plunger, a movable raceway, and raceway operating mechanism including a roller on one member and a cam slot in the other, and means for 100 changing the outline of the slot during the latter part of the movement of the plunger in each direction.

7. A machine for setting fasteners, having 105 in combination, a reciprocatory plunger, a movable raceway, and raceway operating mechanism including a roller and cam slot having its operative edges differently shaped, and means for positively holding the roller 110 in contact with different edges of the slot during the movements of the plunger in opposite directions.

8. A machine for setting fasteners, having 115 in combination, a reciprocatory plunger having a roller, and a raceway having a pair of relatively movable plates provided with slots of different shapes through both of which the roller on the raceway extends.

9. A machine for setting fasteners, having 120 in combination, a reciprocatory plunger having a roller, a raceway having a slot with a wide portion, and a plate movably mounted on the raceway and having a narrow slot so disposed as to confine the roller on the plunger when the roller is located in the 125 wide portion of the raceway slot.

10. A machine for setting fasteners, having 130 in combination, a reciprocatory plunger having a roller, a raceway arranged to be moved toward and from the plunger at dif-

ferent points in the path of the plunger, and a pair of coöperating cams for positively controlling the movement of the raceway at all times.

5 11. A machine for setting fasteners, having in combination, coöperating setting dies, a single operating shaft, toggle mechanism interposed between the shaft and one of said dies, an oscillatory cam for moving the other die, and a lever operated from said shaft for oscillating said cam.

10 12. A machine for setting fasteners, having in combination, a machine frame, a shaft extending transversely across the front of the frame, two toggle mechanisms each having one link mounted on said shaft, punching and setting devices arranged to be operated through said toggle mechanisms respectively, a driving shaft, and clutch mechanism for connecting either of said toggle mechanisms to said driving shaft independently to operate the corresponding punching or setting device.

15 13. A machine for setting fasteners, comprising fastener-setting mechanism, a movable raceway for supplying fasteners thereto, a cam for operating the raceway, and mechanism for transmitting motion from the cam to the raceway, the latter said mechanism including relatively adjustable parts and screw-threaded means arranged to adjust said parts so as to shift one limit of movement of the raceway.

20 14. A machine for setting fasteners, having in combination, an operating shaft, a pair of relatively movable dies operated from said shaft, a raceway for supplying gromets to one die movable transversely of the machine, a raceway for supplying washers to the other die movable at right angles to that first mentioned, and mechanism for operating both raceways from said shaft.

25 15. A machine for setting fasteners, having in combination, coöperating setting dies, a plunger for one of said dies, and a peripheral cam arranged to take the thrust of the die and having a cam track parallel to its periphery with connections thereto for retracting the plunger.

30 16. A machine for setting fasteners, comprising setting mechanism including a mov-

able setting tool, an actuator, means for transmitting movement from said actuator to said tool, and means arranged to take the stress of said tool from said transmitting means when the tool is in the act of setting a fastener.

35 17. A machine for setting fasteners, comprising coöperative setting tools, a movable raceway arranged to supply fasteners to one of said tools, a reciprocatory member, a cam-plate and a cam-roll one of which is carried by the raceway and the other by said reciprocatory member, said cam-plate having a cam-slot provided with non-parallel sides 60 in which slot said roll is received, and means arranged to maintain said roll in contact with said non-parallel sides alternately as the reciprocatory member is moved back and forth.

40 18. A fastener-setting machine comprising a frame, a shaft journaled therein, a table arranged to sustain portions of the work in operative positions, two disconnectible clutch mechanisms carried by said shaft, a punching tool and a setting tool both overhanging said work table and arranged to slide in bearings in said frame, means operable by one of said clutch mechanisms to operate the punching tool, and means operable 65 by the other clutch mechanism to operate the setting tool.

45 19. A machine of the character described comprising a unitary frame, work-punching mechanism and fastener-setting mechanism 70 both arranged in said frame so as to provide an unobstructed straight course from one to the other in which a piece of work may lie in operative position relatively to both said mechanisms simultaneously and so that a portion of the work may follow a substantially straight course from the punching position to the fastener-receiving position, a work table arranged to support the work in 75 operative position relatively to both said mechanisms, and two disconnectible clutch mechanisms arranged in said frame so as to operate the first two said mechanisms respectively.

50 In testimony whereof I have signed my name to this specification.

PERLEY R. GLASS.
